UNITED STATES PATENT OFFICE.

GEORGE M. MAYER, OF HIGHLAND PARK, ILLINOIS, ASSIGNOR TO ATWATER MANUFACTURING COMPANY, OF NORTH CHICAGO, ILLINOIS, A CORPORATION.

DESIGN FOR A BARBER-POLE.

41,728.

Specification for Design. Patented Aug. 29, 1911.

Application filed June 5, 1911. Serial No. 631,468. Term of patent 14 years.

To all whom it may concern:

Be it known that I, GEORGE M. MAYER, a citizen of the United States, and a resident of Highland Park, in the county of Lake and State of Illinois, have invented a certain new, original, and ornamental Design for Barber-Poles, of which the following is a specification, reference being had to the accompanying drawing, forming part thereof.

The figure is a view in elevation of a barber pole showing my new design.

I claim:

The ornamental design for a barber pole, substantially as shown.

GEO. M. MAYER.

Witnesses:

JAMES H. PEIRCE,
KATHARINE GERLACH.
